SIGNAL LAMP

John H. Diedring, Anderson, Ind., assignor to
General Motors Corporation, Detroit, Mich., a
corporation of Delaware

Application November 13, 1941, Serial No. 418,897

2 Claims. (Cl. 177—329)

My invention relates to signal lamps for military vehicles.

In designing a signal lamp for a military vehicle it is necessary to keep in mind the fact that the signal must not be visible to enemy aircraft. It is necessary, therefore, to provide a signal lamp having a limited visibility from above. I have met this limited visibility requirement by the provision of a pair of spaced windows disposed before the light source. These spaced windows are sealed in a unit which is removable and replaceable as a whole.

It is the primary object of my invention to provide a pair of spaced windows disposed before a light source and sealed in a unit which is substantially dust and moisture proof.

Figure 1 of the drawing is a front elevation view showing a signal lamp built according to my invention.

Figure 2 is a side view with parts broken away and in section showing details, and

Figure 3 is a rear elevation view of my sealed unit.

A casing 10 of any suitable sheet material such as metal is shown as forming part of a lamp housing. A cover plate 12 completes the lamp housing. Suitably disposed in casing 10 on a bracket 14 is a socket 16 carrying light bulb 18. Bracket 14 is secured to casing 10 by a mounting means such as a stud 20 having a shoulder 22 which bears against bracket 14. Stud 20 extends through bracket 14, casing 10 and a mounting bracket 24 and is suitably held in place as by staking 26 to hold these parts together.

The forward end 28 of bracket 14 is bent upward to provide a screw threaded opening to receive cover screw 30. An opening 32 is provided on the underside of casing 10 to permit the draining of any moisture which may accumulate in the casing because of condensation or leakage through the top. Opening 32 is protected to a limited extent against the direct entrance of foreign matter by bracket 14 which is provided with a recess or kink 34 to avoid blocking the opening 32. Mounting stud 20 is provided with a longitudinal opening 36 through which may pass lead wire 38 for one terminal of the bulb. The other terminal may be grounded. The casing is provided at its upper side with a recess or notch 40 to receive a cooperating bracket 42 suitably secured to cover plate 12 as by a rivet 44. A gasket 46 of any suitable material such as rubber may be provided to effect a seal between cover plate 12 and casing 10.

Cover plate 12 is provided with a walled open-

ing, or aperture extended along the longitudinal axis of the lamp, to form a compartment 50. The forward opening of compartment 50 may have inturned edges to form a flange 52. Disposed in compartment 50 and near the forward opening is a lens 54 of any suitable light conducting material such as Lucite. Also disposed in compartment 50 but near the inner opening is a screen 56 which may be constructed of any suitable light conducting material such as the commercially known substance Tenite, widely used in the manufacture of light filters. One face of screen or filter 56 may be coated by an opaque substance such as black paint 58. Windows 60 15 may be provided in coating 58. Lens 54 is preferably spaced from screen 56; this spacing may be done by providing lens 54 with inwardly extending members 61. Members 61 could if desired be put on filter or screen 56. The edges of the inner 20 aperture of compartment 50 may be bent inwardly during assembly to form flanges 62 as shown in Figure 3. A gasket such as that shown at 64 may be provided at either opening or at both if desired to assist in rendering the assembly 25 dust and moisture proof.

The optical properties of this signal lamp form no part of the present invention but are separately disclosed and claimed in the copending application of George W. Onksen, Jr., et al., Signal 30 lamps, Serial No. 418,898, filed November 13, 1941.

It is apparent from the foregoing description that I have provided a signal lamp having spaced windows in one wall of the housing which carries a lens, a spacer and a light screen sealed into a 35 substantially dust and moisture proof unit.

I claim:

1. In combination, a lamp housing having an open front end, a light source within said housing, a cover plate adapted to be detachably secured to the open end of said housing, said cover plate being provided with a centrally located passage therethrough extending along the longitudinal axis of said lamp housing and constituted by walls integral with said plate extending substantially at right angles to the plane thereof, a lens mounted within said passage adjacent the front end thereof, a light screen mounted within said passage adjacent the rear end thereof, and an integral extension on said lens adapted to contact 45 said screen to maintain said lens and screen in longitudinally spaced position therein.

2. In combination, a lamp housing having an open front end, a light source within said housing, and a unit assembly adapted to be detachably secured to the open end of said housing, said

assembly including a cover plate having a centrally located passage therethrough extending along the longitudinal axis of said lamp housing and constituted by walls integral with said plate extending substantially at right angles to the plane thereof, longitudinally spaced light transmitting windows mounted within said passage ad-

5 jacent the opposite ends thereof, and means including spacing means between said windows and an integral flange extending inwardly at one end of said passage and flanges on the opposite end thereof which are bent inwardly during assembly to retain said windows in said passage.

JOHN H. DIEDRING.
